UNITED STATES PATENT OFFICE

116,314

DESIGN FOR AN ELECTRIC TRAFFIC TIMING SIGNAL

John J. Roberts, Louisville, Ky.

Application June 13, 1938, Serial No. 77,810

Term of patent 14 years

To all whom it may concern:

Be it known that I, John J. Roberts, a citizen of the United States and a resident of Louisville, in the county of Jefferson and the State of Kentucky, have invented a new, original, and ornamental Design for an Electric Traffic Timing Signal, of which the following is a specification, reference being had to the accompanying drawings, forming a part thereof.

In the drawings:

Fig. 1 is a front elevational view of the face-plate section of an electric traffic signal showing my new design.

Fig. 2 is a view in perspective of an electric traffic timing signal, the broken lines, aside from the front face thereof, showing that the rear casing-portion of the design is a conventional traffic signal.

The dominant features of my design reside in the shape and the arrangement of the tube elements, shown in Figs. 1 and 2 of the drawings.

I claim:

The ornamental design for an electric traffic timing signal, as shown and described.

JOHN J. ROBERTS.
